CLAIM

The ornamental design for a handle, as shown and described.

DESCRIPTION

FIG. 1 is a perspective view taken from the top, rear and right side of a handle showing our new design; FIG. 2 is a front elevational view thereof, the rear elevational view being the mirror image of the front view shown;

FIG. 3 is a top plan view thereof;

FIG. 4 is a right side elevational view thereof; and,

FIG. 5 is a left side elevational view thereof.

The broken line showing of a counter top in FIG. 1 is for purposes of illustration only.

FIG. 1

FIG. 4
